UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PRINTING PLATE

Original application filed June 20, 1924, Serial No. 721,272. Divided and this application filed November 4, 1926. Serial No. 146,274.

This application is a division of my application, Serial No. 721,272, filed June 20, 1924 on a method of casting printing plates without a riser.

5 The principal objects of the present invention are to provide an improved printing plate formed by the method set forth in my original application above identified and to provide this plate in a form in which it is 10 ready to go on the press immediately when cast and without finishing, and to provide a plate having a length less than the length of the matrix from which it is cast with a surface along the edge through which the metal 15 is cast in producing the plate which does not need any finishing after it is cast.

Other objects and advantages of the invention will appear hereinafter.

Reference is to be had to the accompanying 20 drawings in which—

Fig. 1 is an end view of a printing plate constructed in accordance with this invention; and

25 Fig. 2 is a sectional view of a part of the mold in which the plate can be cast showing the edge of the plate as produced therein.

This plate is shown in the drawings as a 30 curved semicylindrical plate for use on rotary printing presses, although the invention can be used for plates for other purposes and of other shapes.

The conventional method of casting plates for rotary printing presses is to pour molten metal into a mold, in which a matrix has been 35 placed. This mold is generally closed on all sides and edges except the edge through which the metal is poured. On this edge a "riser" is formed, which serves the purpose of a feeder, from which the shrinkage within 40 the plate during the cooling process is supplied. This riser is generally so proportioned that it remains in a molten state while the plate is solidifying, so that a reservoir of molten metal is being maintained during that 45 process.

From this it will be seen that it eventually becomes necessary to rid the cast plate of this riser, so that the plate may be produced with a straight finished edge instead of the irregularly shaped mass, formed thereon by the

riser. This makes it necessary to provide a device for severing the riser from the plate proper, usually in the shape of a cutting mechanism of one form or another, according to the idea of the designer and the demands of the machine. The process of cutting off the riser after it has solidified produces a quantity of chips or sawdust which are apt to clog the working parts of the machine and interfere with its operation. It 55 also serves to slow down the production of plates, since a certain number of seconds is required for the act of cutting off the riser.

It has been suggested that the riser while it still is in the molten state, can be cut off by means of a rotating valve or the like. This method has proved defective, however, because among other objections, no way has been found of cutting off the molten riser of a printing plate close enough to the edge of the type matter to avoid reducing the number of lines.

60 This has been because the valve devices proposed have never been able to sever the molten riser at a point nearer to the type than the edge of the matrix clip, which is used to secure the matrix in the mold. Thus, a blank space has had to be left on the plate edge equal in width to the clamping edge of the matrix which shortens the type surface of the plate by as many lines of type at least as the clamping edge of the matrix is wide.

65 As the shortening of the printing surface of a newspaper plate, in the direction of its curvature, reduces the number of type lines the page may carry, and as advertising is sold by the line, it has been necessary to bring the type area of a page to the uttermost edge of the printing plate. It is this limitation 70 that has largely made impracticable the otherwise desirable method of cutting off the riser while in its molten state.

75 The printing plate P in its completed state is produced in a mold and cast in the method set forth in the above identified application without any subsequent finishing. That is, the plate is left as cast with a mold-finished surface 10 located radially and extending to the bolster B of the matrix M. At the rear 80 this surface 10 is merged into a slanting sur-

face 11 which extends to the rear concave surface 12 of the plate. The usual ribs *p* are shown and a projection 43 is produced due to a recess in the surface of the cylindrical core 25 on which the plate is cast. This projection and recess are used as a means of holding the plate positively in one position on the core as the latter rotates to the point at which the plate is taken off. The opposite edge 14 of the plate has a flat edge cast in the usual way.

This plate is cast in a mold such as shown and described in my above mentioned application which involves a casting box 22, core 25, matrix bars 23 and clips 24. These clips hold the matrix just beyond the bolster B. The metal is introduced through a spout 19 from the melting pot 6 and flows against the core 25. When the mold is fully closed as shown in Fig. 2 a shutter or valve 29 is forced in circumferentially up to the position in the mold cavity shown in Fig. 2. While the metal is in a plastic state, this forms the edge of the plate as shown in Fig. 2, with the help of the matrix clips. This forms a surface finished in the act of casting at that point so that the plate is ready to go on the press as it comes from the mold without finishing at this point.

30 Of course the printing plate P is provided on its inner concave face with finishing ribs *p* which are cast in suitable grooves 39 in the core for that purpose. On account of the proximity of the adjacent group of grooves 39 around the cylinder, I find it advisable to provide a lip 40 at the lower end of the shutter 29. This projects downwardly to prevent the metal from running upwardly to the upper half of the core when the shutter 40 29 is partially retracted.

It will be seen that the riser edge of the plate is cast against the surface of the parts 24 and 29. These parts are finished to the proper shape to form the desired configuration of this edge of the plate in the casting operation. Thus the plate can be clamped properly on the cylinder of the press by the usual clamps without any finishing of this edge after it leaves the mold. The ribs *p* may or may not be shaved along their concave surfaces before being clamped to the cylinder. Although there is no riser the advantages of the riser are not lost because the metal is forced into the mold solidly as it is cast. Furthermore, notwithstanding that the metal supply is separated from the casting plate while the metal is in a fluid condition, the plate is of no greater length than a similar plate from which the riser has been sawed after cooling. Neither is any blank space necessary on the plate conforming to the width of the clamping edge of the matrix. Thus the type surface of the plate does not have to be shortened.

65 Although I have illustrated and described

only a single form of the invention, I am aware of the fact that modifications can be made therein by any person skilled in the art without departing from the scope of the invention as expressed in the claim. Therefore I do not wish to be limited in these respects, but what I do claim is:

As an article of manufacture, a curved printing plate having its edge at one side comprising a radial plane surface terminating close to the type surface of the plate and an inwardly slanting surface extending to the concave surface of the plate.

In testimony whereof I have hereunto affixed my signature.

HENRY A. WISE WOOD.
